J. McLAUGHLIN.

Clothes Wringer.

No. 13,684.

Patented Oct. 16, 1855.

UNITED STATES PATENT OFFICE.

JNO. McLAUGHLIN, OF STEUBENVILLE, OHIO.

WRINGER FOR CLOTHES.

Specification of Letters Patent No. 13,684, dated October 16, 1855.

To all whom it may concern:

Be it known that I, JOHN McLAUGHLIN, of Steubenville, in the county of Jefferson and State of Ohio, have invented a new and useful Apparatus for Wringing Clothes; and I do hereby declare that the following is a full, clear, and exact description of the construction and operation of the same, reference being had to the annexed drawing, forming part of this specification, in which—

Figure 1 is an edge elevation; showing the apparatus in operation. Fig. 2 is a face elevation.

Similar letters of reference denote the same part of the wringer.

The nature of my invention consists in combining with a hollow rotary drum through which one extremity of the clothing passes, two ratchet levers acting as will be described to secure the clothing and operate the apparatus.

In the drawing A is a standard supporting the wringer, to be attached to a washing machine, tub or bench as may be desired.

B is a drum, slotted on one side to permit the movement of the lever C, and attached to the standard A by the three supports *a*, which allow it a rotary motion. Upon the inner face of the drum B and embraced by

the supports *a a*, is the ratchet *b*, holding the drum fixed by means of pawl C. Attached to the drum is the small standard D to which is connected by pin *d*, the ratchet lever E. The lever C is movable about the pin *e*, and has upon one edge the teeth *f*, opposite the serrated interior of the drum, so that as the lever C is drawn toward the teeth *h*, the clothes will be tightly grasped and held within the drum, the teeth *l* of ratchet lever E holding the said grasping lever in position through pin *i*.

In operation the clothing is passed over a hook as shown at H in Fig. 1, and confined in the drum as described. The drum is then revolved in direction of arrow, by lever C. When finished, lever E is raised and the clothes released, by the removal of the pressure of the lever C.

I claim—

The serrated rotary drum in combination with the ratchet levers C and E, constructed and operating as and for the purposes specified.

In testimony whereof, I have hereunto signed by name before two subscribing witnesses.

JOHN McLAUGHLIN.

Witnesses:

GEO. PATTEN,
